UNITED STATES PATENT OFFICE.

NICHOLAS WEILER, OF CANTON, ILLINOIS.

BATHER'S PUMP.

Application filed April 17, 1924. Serial No. 707,260.

This invention relates to improvements in a bathing device and has for its object to provide means whereby a bather may pump water over himself, through the manipulation of his foot.

Another object of the invention is to provide a bathing pump embracing a pair of telescopically connected cylinders one of which controls a piston in the other.

Another object of the invention is to provide a pump mounted upon a base upon which a bather is adapted to stand, said pump embracing a foot operated mechanism.

With the above and such other objects in view as may hereinafter more fully appear, I have invented the device illustrated in the accompanying drawings in which:

Figure 1 is an elevational view of my improved bathing pump;

Figure 2 is a top plan view thereof;

Figure 3 is an elevational view, partly in section, showing the device in operation; and

Figure 4 is an enlarged, vertical, sectional view of the device.

Like reference characters indicate like parts throughout the following specification and in the several views in the drawings in which 1 indicates a pump, consisting of a pair of telescopically connected cylinders 2 and 3 the inner cylinder 2 being a pump cylinder and being provided with an inlet valve 4 and an outlet port 5 the bottom wall 6 of the pump in which the valve 4 is located being offset from the base 7 upon which said cylinder 2 is fixedly mounted. The base 7 is of a length to form an extension 8 which is adapted to seat upon the bottom of a top 9 and upon which the bather

is adapted to stand whereby the pump is held fixed while being operated. Connected with the outlet 5 is a passageway 10 having an outlet port 11, controlled by a valve 12 in the compartment 13 from which water

is adapted to pass through the ports 14 into the tube 15 to which is connected a flexible tube 16, said tube having a spray 17 connected to its free end. The cylinder 3 is slidably mounted over the cylinder 2 and has an operating member 18 fixed to its lower edge 19. Projecting from this member 18 is a heel plate 20 by means of which the cylinder 3, may be moved downwardly over the cylinder 2, against the tension of the spring 21, seated between the upper wall

23 of the cylinder 3, said spring being coiled around the piston rod 24, to the lower end of which the piston 25 is connected and operating through the aperture 26 in the wall 22. The base 6 of the pump is provided with an annular, internally threaded flange 27 into which the lower threaded end 28 of the cylinder 2 is threaded.

There are provided in the outer cylinder diametrically opposed slots in which slide bolts 30, the bolts 30 serving also to anchor the cap 22 to the internal cylinder 2.

Having described my invention that which I claim to be new and desire to procure by Letters Patent is:

1. A water pump including a pair of cylinders slideable one over the other, the inner cylinder having a bottom with a water inlet and a water outlet, a valve within said inner cylinder controlling said inlet, a valve controlling said outlet outside of said inner cylinder, and a nipple extending from said last valve, a cap for said inner cylinder, said outer cylinder having opposing guide slots, bolts extending through said slots and forming securing means for said cap. 70

2. A water pump including a pair of cylinders slideable one over the other, the inner cylinder having a bottom with a water inlet and a water outlet, a valve within said inner cylinder controlling said inlet, a valve controlling said outlet outside of said inner cylinder, and a nipple extending from said last valve, a cap for said inner cylinder, said outer cylinder having opposing guide slots, bolts extending through said slots and forming securing means for said cap, a compression spring seated between said cap and the head of the outer cylinder. 85

3. A water pump including a pair of cylinders slideable one over the other, the inner cylinder having a bottom with a water inlet and a water outlet, a valve within said inner cylinder controlling said inlet, a valve controlling said outlet outside of said inner cylinder, and a nipple extending from said last valve, a cap for said inner cylinder, said outer cylinder having opposing guide slots, bolts extending through said slots and forming securing means for said cap, a compression spring seated between said cap and the head of the outer cylinder, a treadle carried by said outer cylinder. 90

4. A water pump including a pair of cylinders slideable one over the other, the inner

cylinder having a bottom with a water inlet and a water outlet, a valve within said inner cylinder controlling said inlet, a valve controlling said outlet outside of said inner cylinder, and a nipple extending from said last valve, a cap for said inner cylinder, said outer cylinder having opposing guide slots, bolts extending through said slots and forming securing means for said cap, a compression spring seated between said cap and the head of the outer cylinder, a treadle carried by said outer cylinder, and a base upon which the pump is mounted whereby the valves are held immersed in water.

15 5. In combination in a pump, a pair of

telescoping cylinders, a pedal member carried by the outer cylinder, longitudinal channels in the outer cylinder, the inner cylinder provided with a cap, means for anchoring the cap to the inner cylinder, the anchoring means extending into the channels.

6. In combination in a pump, a pair of telescoping cylinders, one of the cylinders provided with a longitudinal groove, a pedal carried by the outer cylinder and means carried by the inner cylinder adapted to slide in the groove for alining the pedal.

In testimony whereof I affix my signature.

NICHOLAS WEILER.
